UNITED STATES PATENT OFFICE

2,658,376

AUTOMOBILE DOOR LOCK PROTECTOR

Ray M. Shank, Goshen, Ind.

Application October 9, 1950, Serial No. 189,114

1 Claim. (Cl. 70—455)

1

This invention relates to a new and improved covering for devices such as door handles and key operated locks and is particularly adapted for structures of the character embodied in modern automobile.

An object of the present invention is to provide a covering of the general character indicated, which will protect the lock structure against infiltration of moisture from snow, rain, water from the roadway or when washing the car, which is apt to cause rusting and more particularly the freezing of such moisture within the lock during cold weather which of course would render the lock inoperable.

Another object of the present invention is to provide a cover as described, composed of material such as rubber or other suitable material which covering will be adapted to conform to the contours of the lock portion of the handle and having a passage through which a key may be inserted into the key hole of the lock controlling the handle for use in opening and closing the door.

Another object of the present invention is to provide a covering of the character indicated having a tapered body which will permit water to drain out of the interior should water accidentally be forced therein.

Another object of this present invention is to provide a covering of the character described adapted to be used on either right or left hand handles or handles oppositely directed, without the necessity of being turned inside out.

Still another object of the present invention is to provide a flexible covering for car door handles, having spaced passages in the body portion thereof to permit water to drain out of the interior of said cover should the cover be accidentally damaged or stretched beyond its elastic limit during installation or use.

An additional object of the present invention is to provide a cover of the character described which may have means to permit monogramming each set.

For a better understanding of the invention, together with other and further objects thereof, reference is made to the following description taken in connection with the accompanying drawing, and its scope will be pointed out in the appended claim.

In the accompanying drawing:

Fig. 1 is a top plan view showing a conventional door handle and, in horizontal section, a flexible cover incorporating the principles of the present invention, operably mounted upon the

2

lock portion of the handle, and a key inserted through the end wall of the cover into the lock.

Fig. 2 is a slightly enlarged side elevation of the cover partly broken away and shown in section.

Fig. 3 is an end view of the cover the direction of the view being indicated by the arrow 3 of Fig. 2.

Fig. 4 is a view similar to Fig. 2, but illustrating 10 and showing the wall adjacent the handle opening bifurcated to permit installation of the cover without removing the handle.

Fig. 5 is another view similar to Fig. 2 illustrating 15 a further modification of the cover showing longitudinal passages to facilitate draining moisture from the interior of the cover, and showing means whereby the covers may be monogrammed.

Fig. 6 is a section view of the cover taken on 20 line 6—6 of Fig. 5, with the direction of the view as indicated.

Referring particularly to Figs. 1 and 2 of the drawing, the invention illustrated therein includes a portion of an automobile door 10, the 25 door being provided with a forwardly extended handle generally indicated as 11. The handle 11 which is secured to the door in a suitable and conventional manner, includes an enlarged body portion 12 and a hand grip portion 13. The body portion 12 is provided with a flange or base 14 which cooperates to align the handle with the door. The conventional handle illustrated is of the structure wherein the handle is fixed and the latch is operable by means of cylindrical member 16 which may be pushed inwardly with relation to the body portion 12 of the handle. In this type of structure the lock is enclosed in body portion 12 of the handle, and the lock is operable by means of a key 17 which is inserted in a key 30 slot provided in the outer end of the cylindrical member 16. Since this structure is of standard construction, the lock and bolt operating mechanism is neither illustrated in detail nor is any further specific reference made to such structure hereinafter.

The preferred form of the cover shown in Figs. 1 and 2 is generally indicated as 20 is made of relatively thin flexible material such as rubber or other suitable material, and includes a body portion 21 having tapered side walls 22. The body 21 terminates in a cylindrical extension 23 of reduced diameter. The outer end wall 24 of the extension 23 is thinner than the side walls 22 so as to yield to movement of the key without fracturing, and is provided with a key slot 35

25. As shown in Fig. 2 an aperture 26 is provided in the side wall 22, leaving a narrow wall portion 28. The opening or mouth 26 is shaped to conform with the contour of the hand grip portion 13 adjacent the body portion 12 of the handle. The peripheral diameter of the body 20 and the opening 26 is normally smaller than the peripheral diameter of the handle when the cover isn't mounted. Therefore, when the cover is mounted the wall around the opening 26 is stretched to 10 form a snug fit around the handle portion 13, and the body portion 21 forms a snug fit around the lock portion 12 of the handle as shown in Fig. 1.

It will be apparent that since the cover 20 has 15 tapered side walls, should the cover become stretched beyond its elastic limit through use, and water is forced inside the cover, this water can easily drain out of the interior of the cover away from the latch actuating and key member 16.

When it is desirable to lock or unlock the door in the form of the invention illustrated, the key 17 is inserted through the slot 25 provided in the end wall of the cover 20 into the lock after which the lock may be actuated. Since the cover is flexible, the plunger or member 16 may be pushed inwardly to actuate the latch as heretofore described.

It is to be pointed out that this improved cover is symmetrical about the horizontal medial plane thereof and therefore is adapted to be mounted 30 optionally on either right or left hand handles or on oppositely directed handles without the necessity of being turned inside out.

To mount the cover shown in Figs. 1 and 2 the 35 handle 11 is removed in the conventional manner thus permitting the hand grip portion 13 to be inserted through the opening 26 from the inside of the body portion 21. Then the cover is slid along the hand grip portion 13 until the body portion 12 of the door handle enters and seats within the body portion 21 of the cover, with the hand grip portion 13 protruding through the opening 26, after which the handle 11 is replaced upon the door 10 with the cover 20 mounted on the body portion 12 of the handle as illustrated in Fig. 1.

To eliminate the necessity of removing the handle 11 from the door 10 to install the cover 20, the narrow wall portion 28 may be cut as at 50 30 Fig. 4, to provide ears or flaps 31 which may be spread as indicated in dotted lines, thereby permitting the cover to be installed on the door lock after which, it may be held in place by wrapping the bifurcated end of the cover 20 with 55 rubber tape.

The alternative structure shown in Figs. 5 and 6 comprises modifications of the preferred form of the cover. In the embodiment there disclosed, the cover 20 is provided with longitudinal spaced 60

5 inner grooves or passages 33 which extend from the reduced portion 23 to the large open end of the cover. These passages 33 insure drainage for moisture which may be forced inside of the cover should the cover be accidentally stretched beyond its elastic limit during installation or use.

The modified form of the invention shown in Figs. 5 and 6 also shows means for monogramming each cover. This means comprises a flattened portion 35 indicated in dotted lines, which may be provided on the side wall 22 opposite the opening 26.

While there has been described what is at present considered a preferred embodiment of the invention, it will be obvious to those skilled in the art that various changes and modifications may be made therein without departing from the invention, and it is, therefore, aimed in the appended claim to cover all such changes and modifications as fall within the true spirit and scope of the invention.

I claim:

A cover for a door handle having a body portion and a latch actuating member projecting therefrom, said member embodying a key-operable lock having a keyhole in its outer end, said cover comprising a flexible body symmetrical about the horizontal medial plane thereof whereby it is adapted for installation optionally upon either right or left hand handles without requiring being turned inside out, an elongated end on said body adapted to receive said latch actuating member and having an aperture in the end wall of said elongated end in alignment with said keyhole whereby a key may be inserted into said keyhole without distorting said cover, said body having an aperture in the side wall of said body which permits said body portion of said handle to extend therethrough, and said cover having a groove in its interior surface and extending substantially throughout the length thereof for draining moisture out of the interior of said cover.
